UNITED STATES PATENT OFFICE.

JOHN KERNAN AND ROBERT B. YUILLE, OF PITTSBURG, PENNSYLVANIA,
ASSIGNORS OF ONE-THIRD TO CHARLES W. SARRICKS, OF SAME PLACE.

VALVE-GEAR FOR REGENERATIVE FURNACES.

SPECIFICATION forming part of Letters Patent No. 536,151, dated March 19, 1895.

Application filed January 18, 1895. Serial No. 535,408. (No model.)

To all whom it may concern:

Be it known that we, JOHN KERNAN and ROBERT B. YUILLE, both of Pittsburg, in the county of Allegheny and State of Pennsylvania, have invented a new and Improved Valve-Gear for Regenerative Furnaces, of which the following is a full, clear, and exact description.

The invention relates to valve mechanism for regenerative furnaces, and its object is to provide a new and improved valve gear, which is simple and durable in construction, very effective in operation, easily reversed, and arranged to connect and disconnect the gas supply and the furnace and the latter and the chimney flue.

The invention consists principally of a valve chamber provided with diagonal valve seats crossing each other at or near their middle, and valves fitted to slide on the said seats.

The invention also consists in certain parts and details, and combinations of the same, as will be hereinafter fully described and then pointed out in the claims.

Reference is to be had to the accompanying drawings, forming a part of this specification, in which similar letters of reference indicate corresponding parts in both views.

Figure 1 is a sectional side elevation of the improvement; and Fig. 2 is a transverse section of the same on the line 2-2 of Fig. 1.

The improved valve gear for a regenerative furnace of any approved construction is provided with a valve casing A, formed on opposite sides with openings A' and A'', connected with the gas flues B and B' of the furnace. The top of the valve casing A is provided with a valve seat A, adapted to be engaged by a valve C, to connect the interior of the valve casing with the gas supply flue D and disconnect it therefrom. The open bottom A⁴ of the casing A leads into the chimney flue.

On the sides of the casing A, at the inside thereof, are arranged the diagonal valve seats F and F', crossing each other at or near their middle, as illustrated in Fig. 1. On the valve seats F and F' are fitted to slide alternately the slide valves G and G' respectively, adapted to rest at their outer ends on supports H and H' respectively, secured on the furnace. The outer ends of the slide valves G and G'

are pivotally connected by links I and I' respectively with levers J and J' respectively, fulcrumed at J² on an overhead beam K, as plainly indicated in Fig. 1. The levers J and J' are connected with each other by a link L formed with an extension L' pivotally connected with a hand lever N, fulcrumed on a hanger K' supported on the beam.

Now it will be seen that when the several parts are in the position illustrated in Fig. 1, then the valve G' is in an innermost or closed position while the valve G is withdrawn and the interior upper portion of the valve casing A is connected by the opening A' with the gas flue B leading to the furnace, so that when the valve C is lifted, gas from the flue D can pass through the upper portion of the valve casing A, and through the opening A' to the gas flue B. At the same time products of combustion from the furnace can pass through the flue B' and opening A² into the lower portion of the valve casing A, to pass through the bottom A⁴ to the chimney flue E. Now when it is desired to reverse the position of the valves to reverse the operation of the furnace, then the operator moves the lever N in the direction of the arrow a', see Fig. 1, so that the levers J and J' are caused to swing, and the valve G' is moved outward, while at the same time the valve G is moved inward into a closed position. By this movement of the valves the upper portion of the valve casing A is connected by the opening A² with the flue B', while the other flue B is connected with the lower portion of the valve casing and with the chimney flue E. When it is desired to again reverse the working of the furnace, then the lever N is moved back to the position shown in Fig. 1, so that the valves G and G' are again actuated simultaneously, so that the valve G is moved into an outermost position and the other valve G' into an innermost position. Thus by the simple movement of the lever N, a reversing of the valves and consequently of the furnace takes place.

In one side of the valve casing A and at the middle thereof, is formed an opening adapted to be closed by a plug O, against the outer end of which rests a weighted lever P, to hold the said plug in position. This plug

O serves to prevent gas from escaping the chimney flue.

It will be seen that by the arrangement described one of the valves G or G' is in an outermost position and consequently can readily cool while the other valve is in operation.

It will further be seen that the valves can be readily repaired while in an outermost position without stopping or interfering with the working of the furnace.

If desired, the valve casing may be water-jacketed or lined with fire brick or other suitable material on the inside.

Having thus described our invention, we claim as new and desire to secure by Letters Patent—

1. A valve gear for regenerative furnaces, comprising a valve chamber provided with diagonal valve seats crossing each other at or near their middle, and slide valves fitted to slide on the said seats, substantially as shown and described.

2. A valve gear for regenerative furnaces, comprising a valve chamber provided with diagonal valve seats crossing each other at or near their middle, slide valves fitted to slide on the said seats, and means, substantially as

described, for imparting a simultaneous movement to the said valves so that one moves inward and the other moves outward, as set forth.

3. A valve for regenerative furnaces, comprising a valve casing formed with an open top and bottom and side openings, diagonal valve seats formed in the said casing, and slide valves fitted to slide on the said seats and arranged in such a manner that when one moves inward the other moves outward, as set forth.

4. A valve for regenerative furnaces, comprising a valve casing formed with an open top and bottom and side openings, diagonal valve seats formed in the said casing, slide valves fitted to slide on the said seats and arranged in such a manner that when one moves inward the other moves outward, a plug held in one side of the said casing, and a weighted lever for holding the said plug in position, substantially as shown and described.

JOHN KERNAN.
ROBERT B. YUILLE.
